LINEAR DISTANCE MEASURING DEVICE

Nicholas G. Polydoris, Kenilworth, and Burnell J. Wollar, Barrington, Ill., assignors to ENM Company, Chicago, Ill.

Filed Oct. 13, 1972, Ser. No. 297,235

Term of patent 14 years

Int. Cl. D10—04

U.S. Cl. D10—70

Fig. 1

Fig. 2

Fig. 3

Fig. 4

Fig. 5

FIG. 1 is a front elevational view of a linear distance measuring device, showing our new design;

FIG. 2 is a left-side elevational view thereof, the right side being substantially similar thereto;

FIG. 3 is a top plan view thereof;

FIG. 4 is a bottom plan view thereof; and

FIG. 5 is a rear elevational view thereof.

We claim:

The ornamental design for linear distance measuring device, substantially as shown and described.
